UNITED STATES PATENT OFFICE.

GEORGE N. GODDARD, OF NEWTON, MASSACHUSETTS.

CAP-SPINNING DEVICE.

Application filed October 2, 1918. Serial No. 256,497.

To all whom it may concern:

Be it known that I, GEORGE N. GODDARD, citizen of the United States, and resident of Newton, county of Middlesex, State of Massachusetts, have invented certain new and useful Improvements in Cap-Spinning Devices, of which the following is a specification.

This invention relates to cap spinning and particularly to that type of cap spinning characterized by a rotary yarn-engaging cap member mounted on a central rotary spindle member (either a bare spindle or a spindle carrying a separable bobbin or cop-tube) combined with means for effecting an axial movement of one of said members relative to the other in order to build the yarn-cop such for example as is disclosed in the United States Patent to Victor Belanger 1,020,179, dated March 12, 1912.

Two very serious practical problems are encountered in the practical use of this type of cap spinning; first the control of the yarn tension in order to properly wind a suitable yarn-cop on the spindle member and prevent excessive ballooning of the revolving yarn, and second the problem of securing absolute reliability of action of the cap when, as frequently happens, slight deviation from perfect balance is found to cause undue vibration of the spindle.

It has been proposed to use a splined driving connection between cap and spindle with a retarding element loosely mounted on the cap to engage and retard revolving yarn, but vibration of the spindle causes such loose member to grip upon the cap thereby preventing its intended operation. Another proposed construction employing a gripping spring to releasably clutch the cap on the spindle with the expectation that the spring would expand at high speed to allow the cap to slide on the spindle, encountered the same difficulty beside being difficult of construction and causing the unbalancing of the cap. Therefore, it was abandoned in favor of the splined driving connection.

The present invention is intended to supplement and improve this type of cap spinning by providing a simple practical construction and arrangement which will afford a complete and reliable solution for the difficulties above referred to and other minor

difficulties encountered in this field based on the control of tension by the cap itself. 55

The chief underlying principle of the present invention consists in maintaining such a frictional grip between the cap and its central spindle member that the cap can be quickly brought up to normal speed when the spindle is started so as to prevent the breaking of the yarn while permitting the cap when in normal operation to rotate at enough slower speed than the spindle in order to maintain a suitable tension for the proper winding of the yarn on the spindle member to form the cop. 60 65

Another important feature of this invention consists in affording external lateral support for the cap on opposite sides thereof in addition to supporting the vertical or axial thrust of the cap whereby the lateral pressure is equalized and the cap is prevented from lifting away from its underneath or vertical-thrust support which is occasioned at times by an unbalanced lateral pressure. 70 75

Still another feature of the invention resides in providing the cap with a double internal bearing for engaging the spindle member, one part of which is of relatively larger diameter than the other in order to give a differential rolling contact between the larger bearing and the spindle to cause the cap to rotate more slowly than does the spindle member. 80 85

These and other features of the invention such as the details of construction of the cap and of its bearing or supporting members and of the construction of the lubricating traverse rail carrying the bearing members will be particularly explained hereinafter and will be defined in the claims hereto annexed. 90

In the accompanying drawings I have illustrated a simple and convenient form of construction and arrangement illustrating a practical embodiment of the principles of this invention in which

Figure 1 is a front elevation showing the spindles, the caps and their supporting members, the traverse rail in their relationship to the drawing rolls and thread guides of an ordinary spinning frame; 100 105

Figure 2 is a cross-sectional elevation at right angles to the plane of Figure 1;

Figure 3 is an enlarged detail view showing the cap in central section in its operative relationship to its supporting members and to the spindle member;

5 Figure 4 is a bottom plan view of the cap;

Figure 5 is a detail view showing the spindle adjusting and supporting washers in the spindle rail;

10 Figure 6 is a plan view showing a hollow lubricating traverse rail for supporting the cap sustaining bearing members;

Figure 7 is an end elevation partly in cross section of the hollow lubricating bearing rail;

15 Figures 8 and 9 are enlarged details showing plan views of the interlocking arrangement by which the bearing members are detachably retained in their supporting bolsters.

20 Figure 10 is an enlarged central sectional view showing a cap provided with an internal bearing sleeve surrounding the spindle member.

In the practice of the invention according 25 to the particular form thereof illustrated in the drawings, the spindle rail a' , the traverse rail e , the lifting rods d , the thread board s and the drawing rollers r , the thread eyes s' and the spindles a are of the usual construction employed in spinning frames.

30 So far as concerns the operation of this invention it is immaterial whether the spindle member comprises a single cylindrical spindle blade on which the yarn is wound directly, or a separable cylindrical tube closely fitting over the spindle blade to form a separable cop-tube, hence the term spindle member will be used to signify either constructions since, when the cop-tube is on the 35 spindle blade they form, so far as the spinning operation is concerned, a single central driving member on which the inverted caps are rotatably and slidably mounted.

In the present case the caps are shown to 40 be of the form of cylindrical cups b formed of any suitable material and preferably such as bake-lite which is very light and strong and not affected by moisture. The upper end of each cap is closed except for the central bearing orifice b^5 by means of a disk or top b^2 firmly secured to the cylindrical portion of the cap.

45 For reasons of convenience in constructing and securely holding the cap parts together 50 the construction providing the central bearing for the cap upon the spindle is made in two parts or disks b^2 , b^3 separated from each other a short distance and having co-axial orifices b^4 , b^5 to form two bearing portions, 55 the upper of which is of a size to snugly fit the circumference of the spindle member a but not so tight as to prevent an easy sliding movement thereon. The lower portion 60 of this central bearing as indicated at b^4 is 65 very slightly larger in diameter, say a few

thousandths of an inch, than the upper portion of the central bearing so that the upper portion forms a guide for centralizing the cap on the spindle while the lower portion of the bearing at b^5 has a slight clearance around the spindle member in order to regulate or control the speed of the cap in relation to the speed of said spindle member.

70 Each cap has an internal bearing support on opposite sides of the center, one of said bearing members c having only a lateral engagement against the side of the cap near its lower edge, while the other bearing member d has a beveled supporting surface 80 adapted to engage the lower edge of the cap and thus afford an underneath support for sustaining the vertical or axial weight or thrust of the cap besides affording a lateral support in opposition to the supporting member c to hold and maintain the cap in correct operative position.

85 By reason of the construction above described as seen in Figure 3, the cap will be given a slight tilt toward the beveled bearing member d and slightly away from the lateral bearing member c which results in bringing the lower portion b^4 of the central bearing into close contact with that side of the spindle toward the bearing member c .

90 The two apertures b^4 , b^5 therefore form an elongated bearing slightly larger at its bottom than at its top, and by making these portions of the central bearing in separate disks instead of in one piece, I provide 100 simple and convenient means for effectively securing the central bearing member of the cap detachably in place. It will be observed that near its upper end the cap is left with an internal annular shoulder b' against which the disks b^2 , b^3 abut and against which they are held in firm engagement by means of fastening screws b^6 inserted through 105 apertures in one member and tapped into the other member.

110 It will be obvious that as the cap is thus held in tilted position the spindle member a is frictionally gripped between the two portions of the bearing, and as this relationship remains constant throughout the 115 traverse movement of the cap, there is always maintained a frictional grip or engagement which will be found sufficient not only to maintain the cap at normal operative speed while spinning, but also to start up 120 the cap from a state of rest quickly enough to avoid breaking the yarn end.

125 There are several practical consequences from this principle of supporting the cap so as to form a frictional grip upon the central spindle member during the time it is driven. In the first place, this frictional grip is quite sufficient to start the cap in operation without causing the yarn to break; in the second place, because the engagement 130

is a frictional one there is permitted sufficient circumferential slip or retardation of the cap to cause it to rotate at a materially slower speed than the spindle member rotates, thereby producing the requisite tension on the yarn to wind a firmly built cap on the spindle or bobbin; in the third place, since the lateral pressure of the bearing member *c* against the cap is resisted or equalized by the lateral pressure of the cap against the beveled surface of the bearing member *d*, the cap is maintained in constant and uniform relationship to the spindle and is prevented from lifting away from its thrust bearing which would be the natural consequence of an unbalanced lateral pressure.

In order to slightly vary the gripping pressure of the cap upon the spindle, provision is made for lateral adjustment between the spindle and the bearing members. In order to effect this conveniently I prefer to have the cap-supporting or bearing members mounted in fixed bearings in the traverse rail *e* while making provision for adjusting the spindle laterally in either direction. As the spindle should be firmly held in place after it has been adjusted to correct position, I have provided the spindle-supporting rail with adjusting and positioning means comprising flange washers *f* whose upwardly extending cylindrical flange *f'* is eccentrically bored to snugly fit around the bolster of the spindle. The exterior diameter of this cylindrical flange *f'* is such as to snugly fit the interior of the spindle hole in the spindle rail. The interior diameter thereof fits snugly around the bolster of the spindle rail. A projecting tongue *f''* is also provided to facilitate the rotation of the washer to its proper position of adjustment and also to ascertain, without taking out the spindle, just what the circumferential position of adjustment the washer has at any time.

When the washer is adjusted to properly position the spindle a spindle-fastening nut is screwed home on the outside of the bolster in the usual way and serves to pinch the washer tightly against the underside of the rail while firmly clamping the spindle in position.

If the caps are to be used for spinning coarser counts of yarn which require a stronger tension, and consequently a greater retardation of the cap, this may be effected by making the lower bearing member at *b* slightly larger. Obviously as there is a rolling contact between the lower portion of the central bearing of the cap, the greater the difference between the size of this bearing and the size of the spindle member *a*, the greater will be the retardation of the cap, while on the other hand, reducing the size of this regulating portion of the bearing

tends to give a relative more rapid rotation of the cap.

Besides varying of the central bearing, minor variations in tension may be effected by slightly varying the pressure of the regulating bearing against the spindle member by the lateral adjustment of the spindle.

In order to prevent any injury to the yarn and also to prevent vibration of the cap, I prefer to make those portions of the exterior bearing members *c* and *d* which form the rotatable supports for the cap of a relatively yielding or non-vibrating material. Such material as sole leather serves this purpose, but on account of the tendency of sole leather to become compressed and creased under usage, for reasons of durability, I prefer to use washers or disks of the appropriate size and shape made of a compound of vulcanized rubber and ground textile fibre such as is now commonly used as a substitute for sole leather in the soles of shoes. This material is machined very easily to proper form and size and is found to possess great durability beside affording an excellent non-vibratory cushion against the cap.

Instead of mounting the bolsters *c'* which carry the cap-supporting members in the usual type of traverse rail used on ring frames between the bobbin apertures in the traverse rail, I may employ a lubricating rail in the form shown in Figures 6 and 7 of the drawings. In this case the rail comprises essentially a tubular rail *g* having forwardly projecting extensions or elbows *g'* which are also hollow and made to receive in their vertical bores a bolster *h* provided with upper and lower bearing disks *h'*, *h''* centrally bored to receive the pin *m* of the bearing member to whose head is secured a flanged cup-shaped annular hood or cap *m'* extending down outside the bolster to receive the annular cushion *m''* which forms the contact with the cap. To prevent the pumping of oil I secure to the pin or shaft *m* slightly above the upper bearing *m'* a projecting flange or washer *m''* which extends to throw any oil from the shaft radially outside against the side of the bolster. The bolster is also provided at its top with the inwardly turned lip or ring *h''* so that the oil will not swirl over the top. In order to prevent the accidental lifting or withdrawal of the rotary shaft *m* from its seat or lower thrust bearing *h* the flange or collar *m''* may be made of an oblong form or shape as shown in Figure 8 which very snugly fits a corresponding aperture in the inturned flange *h''* at the top of the bolster. This permits the rotary shaft to be inserted in the proper operative position in its bearings, but as it can be withdrawn only when the collar member *m''* exactly registers with the inturned flange or ring *h''* it can not jump out when rotating yet can be easily withdrawn by hand.

To maintain lubrication of the upper bearing at h' I prefer to give the pintle or shaft m a slightly increasing taper from its lower bearing to a point slightly below its upper bearing so that the oil, under the action of centrifugal force, will tend to seep on the shaft to the upper bearing sufficiently to maintain its lubrication when the oil level is below the level of the upper bearing.

10 At its lower end the bolster is perforated to freely admit oil from the reservoir formed by the tube g . The bottom of the bolster is provided with the central depression or recess in which may be placed a hardened steel ball h^4 to receive the vertical thrust. Each lifting rod d of the traverse rail is provided at its upper end with a supporting bracket d^2 extending transversely of the traverse rail and the spindle rail of approximately L-shape to receive and support the traverse rail g and the forwardly extending bracket or elbow g , the rail being locked in place by a set screw g^3 so as to permit its easy removal.

25 As the weight of the rail is off the center of the lifting rod d a counter weight g^4 running over a sheave g^{31} , may be employed to off-set this lack of balance in order to prevent any possible binding of the lifting rod d in its vertical bearings due to lateral strain or pressure.

With proper adjustment it will be found that the spindles may be driven at speeds much above the spindle speed that is practicable for ring and traveler spinning, and it will also be found that with this arrangement the tension of the yarn will not be adversely affected by the vibration of the spindle. Moreover, with the balanced support for the cap it will be found that the cap instead of disturbing the spindle when rotating at high speed acts as a sort of steadyng bearing to make the spindle run more smoothly.

45 In case the device be used with a cop tube of paper or other material that might be scored or roughened by the friction of the centralizing bearing at the top of the cap, it might be advisable to interpose a bearing sleeve or wear sleeve b^7 such as shown in Figure 10 which is inserted inside the top bearing to permit the rotation of the cap thereon, while protecting the bobbin itself from rotation or wear.

55 Any suitable expedient for keeping the sleeve in position may be employed such as an annular shoulder or lip b^8 . The sleeve fits closely around the bobbin but is not tight enough to prevent it from sliding easily thereon while the centralizing bearings b^2 , b^3 of the cap are free to rotate on the sleeve just as they would rotate on the bobbin itself were no sleeve used. Even though the wear sleeve b^7 have some rotation on the cop tube, the wear will be distributed suffi-

ciently to avoid injury to the tube. Just as in the case where no wear sleeve is employed the lower bearing may be slightly larger than the upper bearing to give a small clearance between itself and the sleeve thereby permitting the above-described arrangement of idlers to cramp the cap in driving relationship to the bobbin.

It will be found that a cap constructed and mounted in accordance with the above-described principles will control the tension of the yarn by its own retardation due to its slower rate of rotation than that of the spindle member unaffected by the vibration of the spindle so that the proper tension is maintained under all reasonable working conditions. Moreover the opposed lateral support afforded the cap when mounted on the spindle may serve to steady the spindle when in action, particularly when the cap is near the top of the spindle member at the time when the spindle would normally be subjected to the greatest strain. This principle of controlling the tension of the yarn by the controlled retardation of the cap is an underlying feature of the invention.

What I claim is:

1. In a cap spinning device the combination with a rotary axial spindle member, of a rotary yarn-engaging cap provided at its upper end with a central bearing surface for engagement with said spindle member to slide axially thereon, and external rotary supporting means engaging said cap and acting to tilt said cap slightly from coaxial relationship to said spindle and thereby cramp the central bearing surface of the cap against the peripheral surface of the spindle member to produce a frictional driving engagement between said surfaces sufficient to cause rotation of the cap while permitting it to slide axially of the spindle, substantially as described.

2. In a cap spinning device the combination of a rotary spindle member forming a driving element, a yarn-engaging cap-building cap having a central bearing surface surrounding the spindle and frictionally engaged therewith to permit both axial and circumferential slip between the peripheral surface of the spindle and the said central bearing surface of the cap, and rotary cap-supporting means mounted exteriorly of the cap in position to incline the cap slightly in relation to the spindle axis in order to maintain a light gripping engagement between said surfaces for causing the cap to be rotated by the spindle, substantially as described.

3. In a cap spinning device the combination with a central spindle member, a rotary cap-building and yarn-retarding cap provided with central bearing engagement upon said spindle member at slightly different levels thereon, and external means for

5 rotatably supporting the cap and maintaining the cap in operative position during rotation with the axis of the cap inclined to the axis of the spindle member, substantially as described.

10 4. In a cap spinning device the combination with a central spindle member, of a rotary cap having a double central bearing in engagement with said spindle member, cap- supporting means for operatively supporting and traversing the cap during its rotation, said cap-supporting means having lateral bearing engagement with said cap to cramp the respective portions of the central bearing frictionally against opposite sides of the spindle member in order to maintain, during starting and normal operation, a frictional gripping engagement with said spindle member, substantially as 20 described.

25 5. The combination with a central rotary spindle-member, a cop-building and tension controlling cap having central bearing frictional engagement with said spindle member, external bearing members rotatably supporting said cap in operative position and having opposed lateral bearing engagement with said cap to hold it frictionally engaged with the spindle member during normal rotation whereby the cap is rotated by the spindle member at a relatively slower speed in order to retard the revolving yarn, substantially as described.

30 6. The combination with a central driving spindle member, a cap having central bearing engagement with said spindle member, and a plurality of cap-supporting members having opposed lateral engagement with said cap and maintaining it in operative frictional driving engagement with said spindle member with the axis of the cap slightly inclined to the spindle axis, and means for traversing the cap axially of the spindle to build a cop.

35 7. The combination with a central driving spindle member, a cop-building and yarn-retarding cap, opposed rotary bearing members for operatively supporting the rotating cap, one of said bearing members having lateral bearing contact against said cap, the other bearing member having a bevelled supporting surface engaging the lower end of the cap to afford axial support for the cap and to oppose the lateral pressure of the 50 first-mentioned bearing member, substantially as described.

40 8. A cap for cap spinning comprising a tubular or cup-like member open at its lower end and provided at its upper end with a central bearing for engaging a central driving spindle, said bearing comprising two circular bearing surfaces having slightly different diameters one of which snugly fits upon the central spindle member, and the 65 other portion being of slightly larger diam-

eter so as to afford a clearance between itself and the central spindle member on the side opposite to its contact with the spindle, substantially as described.

9. A cap for cap spinning comprising a 70 hollow cap open at one end and provided with an internal spacing shoulder near its yarn end, a pair of centrally perforated disks held together against opposite sides of said shoulder, the perforation in one disk 75 being slightly larger than the perforation in the other disk, substantially as described.

10. The combination of a central spindle member, a rotary cop-building and yarn-retarding cap having central bearing engagement upon said spindle member, cap supporting idler members arranged on opposite sides of the spindle each having lateral bearing and supporting engagement with said cap to maintain it in operative position, one 80 of said members affording an axial support against the axial thrust of said cap, and spindle adjusting means for maintaining the spindle positively in the proper position of adjustment to secure suitable bearing engagement between the cap and its supporting idler members, substantially as described.

11. The combination with a series of spindles, a traverse rail mounted adjacent thereto, a series of rotatable idler members having beveled surfaces supported on said traverse rail, another series of idler bearing members arranged on said traverse rail in alternation with said beveled idler members, 90 and a series of cop-building and yarn-retarding caps mounted upon the spindle members and each held in proper operative engagement with said spindle member by and between each pair of adjacent idler 100 members, substantially as described.

12. In a cap spinning device, the combination of a central rotary spindle member upon which the yarn being spun is wound, a centrally apertured rotary reciprocating cap 110 frictionally rotated by engagement between the inside surface of said aperture and the outside surface of said spindle member, and means arranged exteriorly of said cap acting to cramp said cap laterally in relation to the 115 spindle to establish a frictional driving engagement between the inside surface of said aperture and the opposed surface of the spindle, substantially as described.

13. In a cap spinning device the combination of a rotary spindle member, a rotary reciprocating cap, external supporting bearing members engaged said cap in opposition to each other to support the cap in frictional driving engagement with the spindle member, and a year sleeve interposed between the bearings of the cap and the spindle member to protect the spindle member from wear due to contact with the bearings of the cap, 125 substantially as described.

14. In a cap spinning device, the combination of a central rotary driving element, a rotary yarn engaging and cap-building element comprising a cap provided with a concentric bearing surface dimensioned to closely surround the driving element but with sufficient play to allow axial and circumferential slip of one element in relation to the other, and exterior rotary cap supporting means positioned to cause said cap to be pressed laterally against the driving member with sufficient pressure to maintain a frictional driving connection between said concentric bearing surface and its interior driving element to produce the requisite rotation of the cap, substantially as described. 10
15. A traverse rail for a cap spinning machine embracing in its construction a longitudinal supporting member extending parallel to the row of spindles, and a series of transversely arranged hollow tubular oil container bolsters projecting between each adjacent pair of spindles and provided at their forward ends with vertically arranged 20 bearings for supporting rotary cap engaging members.
16. In a cap spinning frame the combination of a tubular traverse rail extending parallel to the row of spindles and forming a common oil reservoir and to the rear of 30 said spindles, a series of short tubular branches projecting forwardly from said traverse rail and in communication therewith to receive oil therefrom and provided at their forward ends with vertical bearings 35 arranged in substantial alignment with the row of spindles, and a series of rotatable idlers mounted in said bearings in position to engage the adjacent caps carried by said spindle members, substantially as described. 40
17. In a cap spinning device, the combination of a rotary driving spindle member, a reciprocatory rotary yarn-engaging cap provided with a central spindle-engaging bearing of somewhat larger internal diameter 45 than the diameter of the engaged portion of the spindle member and rotatable external supporting means arranged to press the cap laterally against the spindle member to maintain a frictional driving contact against one 50 side of said central bearing and thereby cause the cap to rotate at a lower speed than the spindle owing to the difference in the diameters of the spindle member and of the said central bearing of the cap. 55

In witness whereof, I have subscribed the above specification.

GEORGE N. GODDARD.
